UNITED STATES PATENT OFFICE

MILY G. FORSYTH, OF INDIANAPOLIS, AND ROY LASITER, OF GREENWOOD, INDIANA

OVEN RACK SHIFTING DEVICE

Application filed July 9, 1931. Serial No. 549,662.

This invention relates to the art of cooking stove ovens and particularly to means for selectively moving slidable racks within the oven-upon travel of the oven door.

5 A primary object of the invention is to provide means to cause either one or all of the racks within an oven to be pulled outwardly upon opening of the oven door whereby cooking utensils or the like on the racks 10 may be readily accessible without having to reach back to within the oven.

A primary object of the invention is to provide means whereby the oven racks will 15 automatically be returned to their normal positions within the oven upon closing the oven door.

A primary object of the invention is to provide in combination with the rack moving mechanism means whereby any one or all 20 of the oven racks may remain stationary within the oven upon opening and closing the oven door and be independent of the moving mechanism.

A further primary object of the invention 25 is to provide means whereby the moving mechanism may engage any rack and carry it along therewith at the will of the operator.

These and other objects, such as the new 30 and novel combination of the particular elements as will be set forth in the accompanying claims, will become apparent in the following description of the invention, as illustrated in one particular form in the accompanying drawing, in which

35 Fig. 1, is a fragmentary front elevation of an oven embodying our invention;

Fig. 2, is a vertical longitudinal section on the line 2—2 in Fig. 1; and

40 Fig. 3, a detail in top plan view of the oven rack engaging and releasing means.

Like characters of reference indicate like parts throughout the several views in the drawing.

45 Within the oven 10 are mounted the two racks 11 and 12 to be horizontally slidably carried between the channel bar guides 13, 14 and 15, 16 in the usual and well known manner. In order to vary the spacing between the racks and between the top and bottom of the oven, additional guides 17, 18 and

19, 20 are provided to receive the racks. All of these rack guides are spaced inwardly from the side walls of the oven by being supported and secured by their ends to the corner posts 55 of the oven.

On each side of the oven, between the rack guides and the side walls, are fixed in parallel relation, the upper track 21 and the lower track 22, each having an opposing U-shaped channel from which a supporting leg extends over and against and secured along the oven side wall. A slide 23, consisting essentially of a rectangular shaped frame is slidably carried within the channels of and between the upper and lower tracks 21, 22.

A link 24 has its lower end dropped freely through a slot 25 cut in the horizontal part of the leg extending from the lower track 22 at a location a trifle forward of the mid-point thereof. The upper end of the link 24 is pivotally connected to the front member of the slide 23 and a door link 26 has its rear end pivoted to the link 24 between the track 22 and the slide 23. The door link 26 passes 70

freely through the corner post 27 and out to the oven door 28 to be pivoted thereto by its forward end, whereby opening of the door 28 will pull the link 26 forwardly to rock the link 24 about its engagement with the track 22 to in turn pull the slide 23 forwardly 75 along the tracks 21, 22, the travel of the slide being multiplied as compared to that of the link 26 by reason of the leverage set up 80 through the link 24.

85 Short channel bars 29, 30, 31, and 32 are fixed to the rear vertical member of the slide 23 to extend respectively over and above each of the rack guides, the legs of the channel bars being turned upwardly, and in each of the bars is loosely positioned a short bar 33 to have its inner end pivoted to and rockably carried between the legs of the channel bar whereby the bar 33 will normally rest horizontally along the channel bar but may be 90 rocked upwardly therefrom. The outer free end of the bar 33 has a plate 34 fixed thereto in vertical relation. This plate 34 has a central notch 35 cut in its lower edge, from either side of which notch, the plate curves or slopes 95 upwardly, Fig. 2.

The oven racks 11 and 12 are formed in the usual manner by welding a number of wires across a rectangular wire frame. To the outermost of each of these welded wires is rockably secured thereunder the release wire 36 in parallel relation thereto. The forward end of the wire 36 has an out-turned end 37 while the rear end is in-turned to be adapted to be carried into the path of the plate 34.

Referring principally to Fig. 2 of the drawing, the upper plate 34 is here shown as being in its normal position with the rear transverse wire of the rack 11 engaged by the notch 35 of the plate. As the door 28 is opened and lowered (the door being here shown as of the type hinged to the oven by its bottom edge), the connecting link 26 rocks the link 24 to pull the slide 23 forwardly to, in turn, through the plate 34, pull the rack 11 forwardly to cause it to extend somewhat from the oven. Closing the door 28 returns the oven rack 11 through the same mechanism. The lower rack 12 is here shown as not being engaged by one of the lower plates 34 and hence remains stationary. By closing the door 28, the rack 12 may be engaged by the plate 34 adjacent thereto as the plate 34 is moved rearwardly to have it lift up over the rear rack transverse member and drop down thereover to have the notch 35 therein engage about the transverse member, the plate being rocked upwardly by reason of its rear inclined edge sliding over the rack member. Either or both racks may be released from the engaging plates 34 by pushing downwardly on the ends 37 of the release wires to cause the other ends to push upwardly and lift the plates 34 out of engagement with the racks. Either or both racks may also be released from the plates 34 and pushed back into the oven against the rear wall thereof so that the rear transverse members of the racks are carried back of the rear limit of travel of the plates 34 whereby the plates can not then engage the rack members and the door 28 is then free to be opened and closed without moving the racks. From that innermost position, either or both of the racks may be pulled forwardly slightly to slide the rear members thereof into engagement with the plates 34.

Similarly, the racks may be released from the plates 34 and pulled out freely from the oven and then returned to, be engaged by the plates 34 by entering the rack transverse members under the plates 34 from the forward inclined edges thereof. Each of the plates 34 drop normally by the pull of gravity and remain dropped until lifted by the oven rack members being pushed against the cam-like inclined front or rear edges.

While we have here shown and described our invention in the one best form as now known to us, it is obvious that structural changes may be made therein without depart-

ing from the spirit of the invention and we, therefore, do not desire to be limited to that precise form, nor any more than may be required by the following claims.

We claim:

1. In an oven, the combination with a slideable rack and a door, of a slide, connecting linkage between the door and the slide, and a plate rockably carried on the slide in the path of said rack, said plate being adapted to rock into engagement with the rack upon travel thereover, the oven being of such length that the rack may be positioned to such a rearward extent that when the slide and plate are in their most rearward position the rack is out of engagement with the plate. 70

2. In an oven, the combination with a slideable rack and an oven door, a plurality of vertically spaced rack guides, a slide positioned between the rack guides and the oven wall, a link pivoted to the slide and having its free end dropped through a slotted member, a link pivotally interconnecting said link between said slide and the slotted member and the said oven door, and a rack engaging plate hinged to said slide to swing upwardly adjacent each of said rack guides, and a rockable plate release wire on the rack having an extension laterally under the plate. 75

3. In an oven, the combination with a slideable rack and an oven door, a plurality of vertically spaced rack guides, a slide positioned between the rack guides and the oven wall, a link pivoted to the slide and having its free end dropped through a slotted member, a second link pivotally interconnecting said first link between said slide and the slotted member and the said oven door, and a rack engaging plate hinged to said slide to swing upwardly adjacent each of said rack 80 guides. 85

4. In an oven, the combination with a slideable rack and an oven door, a plurality of vertically spaced rack guides having a channel bar extending over the rack guides, a slide positioned between the rack guides and the oven wall, a link pivoted to the slide and having its free end dropped through a slotted member, a second link pivotally interconnecting said first link between said slide and the slotted member and the said oven door, and a rack engaging plate carried by said slide adjacent each of said rack guides, each of said plates being hingedly supported in a channel bar extension from the slide to be free to be rocked into engagement with the rack. 90

5. In an oven, the combination with a slideable rack and an oven door, a plurality of vertically spaced rack guides, a slide back of the guides, a link pivoted to the slide and having its free end dropped through a slotted member, a second link pivotally interconnecting said first link between said slide and the slotted member and the said oven door, and 95

a rack engaging plate carried by said slide adjacent each of said rack guides, each of said plates being hingedly supported from the slide to be free to be rocked into engagement with the rack, and each of said plates having its under edge centrally notched and inclined upwardly therefrom both forwardly and rearwardly.

6. In an oven, a rack, a plurality of vertically spaced rack guides, a slide adjacent said guides, a rockable rack engaging plate carried by the slide at each rack guide, and a plate release wire carried by the rack the oven being of such length that the rack may be positioned to such a rearward extent that when the slide and plate are in their most rearward position the rack is out of engagement with the plate.

7. In an oven, a rack, a plurality of vertically spaced rack guides, a slide adjacent said guides, a rockable rack engaging plate carried by the slide at each rack guide, a plate release wire carried by the rack, a door on the oven, linkage connecting the slide and the door to effect movement of the slide upon movement of the door, the rearward travel of the slide being limited to permit the rack to remain at will in a rear position out of engagement with said plate.

80 In testimony whereof we affix our signatures.

MILO G. FORSYTH.
ROY LASITER.
